GRAFTING IMPLEMENT

Glenn Masuo Masunaga, Wahiawa,
Territory of Hawaii

Application August 5, 1943, Serial No. 497,481

2 Claims. (Cl. 47—6)

This invention relates to new and useful improvements in grafting devices and more particularly to a device for facilitating the cutting of scions for grafting.

The principal object of the present invention is to provide a grafting tool whereby in cutting scions a perfectly straight cut can be obtained and this is necessary in order to perform a satisfactory grafting job.

Another important object of the invention is to provide a grafting tool including a cutter which can be actuated at any desired angle with respect to the scion.

Other objects and advantages of the invention will become apparent to the reader of the following description.

In the drawings:

Figure 1 represents a side elevational view of the implement.

Figure 2 is a side elevational view of the implement looking at the opposite side from that shown in Figure 1.

Figure 3 is a top plan view of the implement.

Figure 4 is a vertical section on the line 4—4 of Figure 1.

Figure 5 is a section on the line 5—5 of Figure 1.

Figure 6 is a perspective view of the blade.

Figure 7 is a section on the line 7—7 of Figure 1.

Referring to the drawings wherein like numerals designate like parts, it can be seen that the implement includes an elongated supporting bar 5 having a clamp structure 6 at each end portion thereof. Each clamp is generally referred to by numeral 6 and includes a pair of jaws 7, 7 (see Figure 4) hingedly secured as at 8 to the bar 5 and each having a resilient lining 9 at its inner side. A clamp screw 10 serves to draw the upper ends of the jaws together or separate the same. The purpose of these clamps is to firmly hold the scion in place.

A lug 11 on one end of the bar 5 has a threaded opening therein for a clamp screw 12 and this clamp screw is operative against one end of the scion.

Depending from the bar 5 is a semi-circular shaped guide 13 having a substantially 90 degree slot 14 therein, and depending from the intermediate portion of the bar 5 is a lug 15 which has a threaded opening therein to receive a screw 16 which passes through a slot 17 in a cutter bar 18, this cutter bar 18 at its upper end being provided with a blade 19 having a cutting edge 20 and along one edge having slots 21 through which

securing elements 22 can be disposed for securing the blade to the upper end of the bar. Thus it can be seen that the blade projects laterally of the bar 18, this being readily seen in Figure 3.

Where the slot 17 intersects the slot 14, a bolt 23 extends therethrough and is equipped with a nut 24. A cap plate 25 straddles the semi-circular shaped member 13 and the bolt 23 also passes through this cap 25. A set screw 26 is disposed through the cap and can be screwed against one edge of the semi-circular member 13.

The lower end of the cutter bar 18 has a handle 27 whereby the cutter bar 18 can be actuated.

An elongated blade 28 is secured to the unslotted portion of the semi-circular shaped guide 13 and can be used for trimming branches and the like off of scions.

It can now be seen that with the scion properly held in position by the clamp 6 and the clamp 12, the cutter bar 18 can be adjusted to the desired angle and when this has been satisfied, the bar 18 can be jerked downwardly and the blade 19 will cut through the scion at the desired angle, making a perfectly straight cut.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. A device for cutting scions for grafting, comprising a horizontal elongated supporting bar, spaced clamps carried by said bar for securing a scion on the latter parallel with the same, an arcuate guide rigid with and depending from one side of said bar, an inclined cutter bar extending across said supporting bar and said guide and projecting above the supporting bar between said clamps, a cutter blade carried by the upper end of said cutter bar and projecting laterally of the latter over said supporting bar, a handle on the lower end of said cutter bar, means connecting said cutter bar to said supporting bar for pivotal movement relative to the latter about an axis coincident with the center of curvature of said arcuate guide and for longitudinal sliding movement relative to the supporting bar, and a guide member for said cutter bar adjustable along said guide to vary the angle of the cutter bar relative to the supporting bar, whereby the scion may be severed between said clamps by said cutter bar.

ter blade at a desired angle upon pulling the cutter bar downwardly.

2. A device for cutting scions for grafting, comprising a horizontal elongated supporting bar, spaced clamps carried by said bar for securing a scion on the latter parallel with the same, an arcuate guide rigid with and depending from one side of said bar and having an arcuate slot therein, an inclined cutter bar extending across said supporting bar and said guide and projecting above the supporting bar between said clamps, a cutter blade carried by the upper end of said cutter bar and projecting laterally from the latter over said supporting bar, a handle on the lower end of said cutter bar, said cutter bar having an elongated longitudinal slot therein, a lug

rigid with said supporting bar, a screw extending through said slot of the cutter bar and threaded into said lug for connecting said cutter bar to said supporting bar for pivotal movement relative to the latter about an axis coincident with the center of curvature of said arcuate guide and for longitudinal sliding movement relative to the supporting bar, and a screw extending through the slot of said cutter bar and adjustable in the slot of said guide to vary the angle of the cutter bar relative to the supporting bar, whereby the scion may be severed between said clamps by said cutter blade at a desired angle upon pulling the cutter bar downwardly.

GLENN MASUO MASUNAGA.
